US00D701857S

(12) **United States Design Patent**
Ding

(10) **Patent No.:** **US D701,857 S**
(45) **Date of Patent:** **** Apr. 1, 2014**

(54) **MEDIA HOLDER**

(75) Inventor: **Jimmy Ding**, Ningbo (CN)

(73) Assignee: **EBSCO Industries, Inc.**, Birmingham, AL (US)

(**) Term: **14 Years**

(21) Appl. No.: **29/428,656**

(22) Filed: **Aug. 1, 2012**

(51) **LOC (10) Cl.** **14-03**

(52) **U.S. Cl.**

USPC **D14/253**

(58) **Field of Classification Search**

USPC D14/140, 140.8, 142, 243-256, 434, D14/447; D3/215, 218; D2/861; D6/300, D6/310, 467, 553-574; 292/342, 343; D19/90

See application file for complete search history.

(57) **CLAIM**

The ornamental design for a media holder, as shown and described.

DESCRIPTION

FIG. 1 is a perspective view of the media holder in an opened position;

FIG. 2 is a perspective view of the media holder in a closed position;

FIG. 3 is a left elevational view of the media holder as illustrated in FIG. 1;

FIG. 4 is a right elevational view of the media holder as illustrated in FIG. 1;

FIG. 5 is a front plan view of the media holder as illustrated in FIG. 1;

FIG. 6 is a rear plan view of the media holder as illustrated in FIG. 1;

FIG. 7 is a top view of the media holder as illustrated in FIG. 1;

FIG. 8 is a bottom view of the media holder as illustrated in FIG. 1;

FIG. 9 is a top view of the media holder as illustrated in FIG. 2;

FIG. 10 is a left elevational view of the media holder as illustrated in FIG. 2;

FIG. 11 is a right elevational view of the media holder as illustrated in FIG. 2;

FIG. 12 is rear plan view of the media holder as illustrated in FIG. 2; and,

FIG. 13 is a bottom view of the media holder as illustrated in FIG. 2.

1 Claim, 6 Drawing Sheets
